CARL S. ROSE, OF SAN FRANCISCO, CALIFORNIA.

REVERSIBLE ROTARY ENGINE.

1,163,559.

Specification of Letters Patent. Patented Dec. 7, 1915.

Application filed April 6, 1915. Serial No. 20,965.

To all whom it may concern:

Be it known that I, CARL S. ROSE, a citizen of the United States, residing in the city and county of San Francisco and State of California, have invented a new and useful Improvement in Reversible Rotary Engines, of which the following is a specification.

My invention relates to reversible rotary engines wherein a rotatable member having a plurality of radially disposed rotating bores closed at the outer ends thereof, by means of a suitable stationary casing having channels arranged to supply energy to the outer ends of the bores, operates in conjunction with a plurality of pistons slidably mounted within the bores and operatively connected to a stationary shaft set eccentric with the rotatable member; and the objects of my invention are first, to provide an improved unit for generating power that shall be simple of operation and cheap of construction; second, to provide a device of the character described wherein the pistons and bores, or cylinders shall be rotated thereby eliminating the necessity for a fly-wheel or equivalent; third, to provide improved means for regulating the supply of energy to the bores; and fourth, to provide a rotary engine of the character described that may be easily reversible. I accomplish these several features by means of the device disclosed in the drawings forming a part of the present specification, wherein like characters of reference designate similar parts throughout the specification and drawings, and in which—

Figure 1 is a longitudinal vertical sectional view of the device disclosing the arrangement of the bores and the pistons slidably mounted therein, the valves in the upper openings not being shown for the purpose of simplifying the drawings. Fig. 2 is a transverse vertical sectional view of the device disclosing the manner in which the rotatable member is rotatably mounted within the casing and the manner in which the pistons are operatively connected to an eccentric stationary shaft. Fig. 3 is an enlarged sectional view of a portion of the casing disclosing the manner in which the supply

of energy from the channel is regulated by a valve. Fig. 4 is an enlarged plan view of a valve in an open position. Fig. 5 is a view similar to Fig. 4 but with the valve shown closed.

Referring to the drawings, the numeral 1 is used to designate a suitable frame having a driving shaft 2 rotatably mounted therein. To the inner end of the shaft 2 is rigidly secured a rotatable member 3 having a plurality of radially disposed bores 4 therein. Within each bore 4 is slidably mounted a piston 6 which is operatively connected, by means of a suitable connecting rod 7, to a stationary shaft 8 set eccentric to the drive shaft 2 and the rotatable member 3 thereon. Each connecting rod 7 is adapted to engage a guide ring 9 concentric with and secured to the stationary shaft 8, the purpose of which will hereinafter be more fully described.

A suitable casing for the rotatable member 3 is formed by the circular member 12 to which is rigidly secured an annular ring 14 having two semi-circular channels 15 and 16 formed therein. A plurality of radially disposed apertures 17 penetrate the channels 15 and 16 and are arranged to communicate with the bores 4 of the rotatable member 3. The inner ends of the apertures 17, except the three lowermost on each side, are provided with a valve seat 18 having diametrically opposed ports 19 and a pin 21. A valve 22 having an arcuate slot 23 therein adapted to engage the pin 21, is rotatably mounted upon each valve seat 18 and is provided with diametrically opposed ports 24 arranged to register in one position, with the ports 19 of the valve seats 18. Within the outer end of each aperture 17 is secured a suitable stuffing gland 26 within which is rotatably mounted a valve stem 27, the lower end of the said stem 27 being slidably mounted within the valve 22 and rotatably mounted within the center of the valve seat 18. A spring 28 is interposed between the lower end of each stuffing gland 26 and the valve 22, the purpose of which will hereinafter be more fully described. A steam supply pipe 30 supplies steam or energy to the

channel 15 while a similar pipe 31 is connected to the channel 16.

The operation of the device is as follows: The valves 22 are first adjusted to regulate the flow of steam or other suitable energy to the bores 4 adjacent to the channel 15, each valve, beginning with the lowermost, being adjusted to admit more steam or other energy than the one immediately above it so that as the rotatable member 3 and the bores 4 therein move upward, the supply of steam will be lessened, the steam within each bore expanding and moving the piston 6 therein inward and the bore upward simultaneously. As the three lowermost apertures 17 are without valves and therefore admit steam under full pressure to the bores 4 as they pass the said apertures it is evident that the pistons 6 within those bores will be operating under full pressure while the bores above will be operating under the expansion plus an additional head of steam or energy admitted through the partly opened valves. As the pistons are moved inwardly by the expansion of the steam or other suitable energy, it is evident that the said movement will impart a rotary movement to the connecting rods 7 which will react through the medium of the pistons 6 and 30 rotate the rotatable member 3. As each bore 4 reaches the uppermost point in the rotation of the member 3 the piston 6 in that bore will be at the lower limit of its stroke. As the bore descends on the other side the outward movement of the piston 6 will assist the exhaust of the steam or energy through the apertures 17 and the valves therein into the channel 16 until the bore reaches the three lowermost apertures when 40 any remaining steam will be completely exhausted therefrom through the three lowermost apertures 17. The exhausted steam will then be conducted from the casing by means of the connection or pipe 31. If the supply of energy is introduced through the pipe 31 instead of through the pipe 30, by means of any suitable reversing valve gear not shown, it is evident that the operation heretofore set forth will obtain except that the rotatable member 3 will rotate in the opposite direction. While rotating in the opposite direction the exhaust steam may be readily exhausted through the valves 22 which heretofore admitted steam for the reason that the said valves 22 are held onto the seats 18 by means of the springs 28 which will permit the valve 22 to lift and the steam to escape from the bores 4 and into the channel 15 which then becomes an 50 exhaust instead of a supply channel as hereinbefore described.

It is obvious from the foregoing that I have provided an improved rotary engine which may be easily and readily reversed by

simply introducing the steam or other energy into the exhaust instead of the intake channel.

Having thus described my invention what I claim as new and desire to secure by Letters Patent is—

1. A rotary engine comprising a circular rotatable member having a plurality of radially disposed bores therein; a stationary shaft set eccentric to the rotatable member; a piston slidably mounted within each bore and operatively connected to the stationary shaft; a suitable casing arranged around the rotatable member and having two semicircular channels therein and radially disposed apertures penetrating the said channels, the inner ends of one-half of the apertures being arranged to convey energy from one semi-circular channel to approximately one-half of the bores at a point beyond the pistons therein and the inner ends of the other half of the apertures being arranged to serve as exhaust ports between the bores and the other semi-circular channel; and means secured within the apertures and adapted to regulate the flow of energy to the bores. 90

2. A rotary engine comprising a circular rotatable member having a plurality of radially disposed bores therein; a stationary shaft set eccentric to the rotatable members; a piston slidably mounted within each bore and operatively connected to the stationary shaft; a suitable casing arranged around the rotatable member and having two semi-circular channels therein and radially disposed apertures penetrating the said channels, the inner ends of one-half of the apertures being arranged to convey energy from one semi-circular channel to approximately one-half of the bores at a point beyond the pistons therein and the inner ends of the other half of the apertures being arranged to serve as exhaust ports between the bores and the other semi-circular channel; and suitable valves secured within the apertures and adapted to regulate the flow of energy to 110 the bores. 100

3. A rotary engine comprising a suitable frame; a drive shaft rotatably mounted within the frame; a circular rotatable member secured to the drive shaft and having a plurality of radially disposed bores therein; a stationary shaft secured to the frame and eccentric with the rotatable member and the drive shaft; a piston slidably mounted within each bore and operatively connected to the stationary shaft; a suitable casing secured to the frame and arranged around the rotatable member and having two semi-circular channels therein and a plurality of radially disposed apertures penetrating the channels, the inner ends of one-half of the apertures being adapted to convey energy from one semi-circular channel to approxi- 115 120 125

mately one-half of the bores, and the inner ends of the other half of the apertures being arranged to serve as exhausts for the other half of the bores; and suitable valves within the apertures and adapted to regulate the supply of energy therethrough.

In witness whereof I hereunto set my sig-

nature in the presence of two subscribing witnesses.

CARL S. ROSE.
